WELL CASING ATTACHMENT

Domer Scaramucci, Oklahoma City, Okla., assignor to Oil Equipment Engineering Corporation, Oklahoma City, Okla., a corporation of Oklahoma

Application October 4, 1939, Serial No. 297,926

12 Claims. (Cl. 166—9)

The present invention relates to well casing attachments and pertains particularly to cementing shoes which guide and float the well casing as well as wash down the hole ahead of the casing.

It is the principal object of the invention to provide practical means for accomplishing all of these enumerated functions efficiently with a simple casing attachment.

More specifically stated, it is intended to provide a guide and float shoe with side ports arranged to open and discharge cement after the casing has been set on the bottom of the hole. Novel port means are provided for ejecting the cement upwardly in a circular spray. This port means is characterized by an annular header and a resilient sealing or valve ring.

In one form of the invention the resilient sealing member is constructed and arranged to function also as the packing member in a pack-off shoe.

It is proposed also to minimize cement contamination of sand below the shoe and to avoid undesirable washing of the walls as the casing is lowered. Among the additional important purposes which the instant invention achieves are the elimination of valve constructions requiring sliding parts and spring means which are difficult to drill up, and external devices which objectionably increase the diameter of the shoe attachment. It is also noteworthy that any possibility of uneven distribution of the cement or channeling is avoided by the annular header or groove which connects with the discharge ends of the lateral or side ports within the valve ring.

These and other objects and features of the invention will be apparent from a reading of the following detailed description of one preferred embodiment and a modified form thereof, when taken with the accompanying drawing, in which

Fig. 1 illustrates the casing shoe attachment by means of a longitudinal section;

Fig. 2 is a longitudinal section similar to Fig. 1, but differing therefrom in the position of certain parts and the showing of the attachment in relation to the bottom of a well bore;

Fig. 3 shows the plug part of the attachment in side elevation;

Fig. 4 represents a top plan view of the part shown in Fig. 3;

Fig. 5 is a cross-sectional view of the assembled attachment taken on the plane of line A—A in Fig. 1;

Fig. 6 is a longitudinal section of a modified form of attachment;

Fig. 7 is a longitudinal section similar to Fig. 6, but differing therefrom in the position of certain parts and the showing of the attachment in its relation to a well bore; and

Fig. 8 shows in side elevation the plug part of the modified attachment.

In the casing attachment which is embodied in the device of Figs. 1 to 5 inclusive, 10 indicates a cylindrical casing shoe, which may be of plow steel and which is provided with internal threads 12 in its upper end adapted to be connected to the end of a casing section. The lower end portion of shoe 10 has an integral threaded connection with a generally cylindrical plug 16 of a drillable material, for example, aluminum or cementitious material. A pointed or rounded lower end 18 of the plug 16 extends below the shoe 10, forming at its upper part a fair continuation of the outer surface of said shoe.

A longitudinal passageway 20 of relatively large cross-section extends through plug 16 for purposes now to be set forth. Intermediate of the passageway 20 there may be provided an enlarged valve chamber 22 containing a ball check valve 24 which is drillable, and buoyant in well fluid or cement slurry. Such valves are generally made of bakelite. When check valve 24 is floated or forced upwardly, it closes the upper end of passageway 20 and prevents fluid from passing upward into the shoe 10. The valve chamber is designed to permit downward fluid flow at all other times, namely, when fluid pressure pushes valve 24 down into an open position (Fig. 2).

In the lower or guide end 18 of plug 16, a number of passages 26 extend in a generally radial direction from the lower end of passageway 20. Preferably, these passages are uniformly spaced in a horizontal plane, as illustrated in Figs. 1 and 5 where four passages are employed. An annular header 28 is formed at the outer ends or ports of passages 26, as by providing a deep circumferential groove or channel of arcuate shape in the plug 16 (Fig. 3).

Of particular importance is the flexible valve ring 30 which normally closes the outer side of the header 28. It has been found expedient to mold this ring member 30 from a good grade of rubber, reinforced if necessary, and of sufficient thickness to provide the required stiffness. As illustrated in Figs. 1 and 2, valve ring 30 is close fitting and of a height adequately to cover the discharge header 28 and its connecting passages 26. Note is to be taken that the rubber ring 30 has the form of a tapered sleeve of approx-

imately the slope of the closely encircled portion of the pointed or guide end 18 of plug 16. The lower edge of rubber ring 30 is anchored in plug 16 below header 28, and is shouldered with a downwardly extending flange 32 for this purpose.

Referring to Fig. 2 in which the upper portion of valve ring 30 is flexed in its discharge position, it will be observed that the small angle of incidence or impingement with the vertical wall of the well bore WB is such as to produce an effective upward projection of cement from the shoe.

A description of the manner of operation of the attachment constituting the present invention will now be given. From what has been disclosed in the foregoing paragraphs, it will be understood that the attachment is mounted on the lower end of a string of well casing and that the shoe threads 12 are intended for making the connection. Initially, the casing will be floated by the action of ball check valve 24 closing the passageway 20 to flow upward into the casing. Any time during the running-in of the casing circulating fluid under high pressure can be forced down the casing to unseat the ball check valve 24 and open the lower end of passageway 20. The discharge from the main passageway 20 will be highly efficient in removing bridges and generally cleaning the bore hole ahead of the casing shoe. By preventing lateral discharge of circulating fluid at this time, the action of the passageway 20 will be rendered most effective, since there will be no diversion of pressure fluid. If the passages 26 were not closed, the fluid discharge through them would tend to remove the protective wall layer and cause the hole to cave.

After the casing has been landed on the bottom of the hole, circulating fluid and cement will be ejected upwardly, as seen in Fig. 2 which shows the flexed or open position of sealing ring 30. The combined effect of the plurality of outwardly extending passages 26, their annular header 28, and the resilient ring 30 will produce an upwardly directed circular jet or spray of cement which will be so uniform as to preclude channeling.

While the pack-off shoe embodiment of the invention shown in Figs. 6, 7, and 8 includes the features which have been described in detail, it has a different arrangement of lateral passages and an extended form of resilient valve ring.

In this instance a short casing shoe 100 is threaded internally at its upper end, as indicated by reference numeral 120. An internal threaded connection 140 at its lower end secures it to a frangible, drillable plug 160 which has a long conical guide end or extension 180 below shoe 100. A similar longitudinal passageway 200 passes through plug 160 with an intermediate valve chamber 220 for a buoyant ball check valve 240 intermediate its ends.

Four passages 260 extend outwardly from the valve chamber 220 and connect with a circumferential header 280 formed by a relatively deep groove in the lateral surface of the plug guide end 180 a short distance below the end of shoe 100. A uniform spacing and radial arrangement of passages 260 are illustrated as the preferred relation.

The passages 260 and their header 280 are closed by a resilient valve ring 300 of uniform and substantial thickness retained in a complementary channel 310 in the lower end 180 of plug 160. Due to its tapered shape, extent and resili-

ent nature, the ring or sleeve 300, which may be molded from rubber of suitable composition, needs no other anchoring means.

In the instances where a rat-hole, RH in Fig. 5, is drilled into the oil sand, the modified attachment with its long, tapered, resilient sleeve 300 serves also as a formation packer, and cement may be discharged laterally past the upper end of the resilient valve and packer ring which is above the shallow rat-hole. Otherwise, the modification which has just been described functions the same in operation as the previously set forth form of the invention.

Great simplification without reduction in efficiency has been obtained by combining the functions of a packer and of a valve for lateral ports in a unitary resilient ring.

Obvious structural changes are all that is required to adapt the outlined principles of guide and float shoe construction to a float collar for combination with a guide shoe.

While the details of two different embodiments of this invention have been disclosed herein, those versed in the art will realize that numerous changes may be made in construction which will come within the scope of the appended claims:

Having thus described my invention, what I claim as new and desire to secure by Letters Patent of the United States is:

1. A well casing attachment comprising a hollow cylindrical member adapted to be connected to the end of a casing section; frangible plug means having a longitudinal passageway secured within the cylindrical member, said plug means being provided with side ports connecting with said passageway and a header channel joining the side ports at the periphery of the attachment; and a resilient valve ring disposed over the header and having its lower portion joined to the attachment so that its upper edge may flex outwardly and uncover the header channel in response to internal fluid pressure.

2. A well casing attachment comprising a cylindrical shoe; a drillable plug with a longitudinal passageway joined to said shoe, said plug being provided with a plurality of passages extending outwardly from its longitudinal passageway and an annular header groove connecting the outer ends of the passages; valve means intermediate the passageway for preventing flow into the casing; and a resilient ring secured to the outer surface of the plug so as to cover the outer ends of the outwardly extending passages and arranged to flex away from the plug at its upper edge to permit fluid to be discharged from said passages.

3. A well casing attachment comprising a cylindrical shoe; a plug with a longitudinal passageway joined to said shoe, said plug being provided with a plurality of equally spaced radial passages extending outwardly from its longitudinal passageway; ball check valve means intermediate the passageway for preventing flow into the casing; and a resilient tapered sleeve secured to the outer surface of the plug so as to cover the outer ends of the outwardly extending passages and arranged to flex away from the plug at its upper edge to permit fluid to be discharged from said passages.

4. A well casing attachment comprising a cylindrical shoe; a frangible plug with a longitudinal passageway connected to the shoe and projecting therefrom, said plug having a plurality of passages extending outwardly from the longitudinal passageway and an annular header groove in its

outer surface joining the outer ends of the passages; and a resilient sealing ring arranged to cover the groove and passage ends, said ring having its lower edge portion anchored in the plug.

5. A well casing attachment comprising a cylindrical shoe; a frangible plug with a longitudinal passageway connected to the shoe and having a pointed end projecting therefrom, said plug having a plurality of passages extending outwardly from the longitudinal passageway and an annular header channel in its outer surface joining the outer ends of the passages; and a resilient sealing ring of rubber arranged to cover the groove and passage ends, said ring having its lower edge portion anchored in the plug.

6. A well casing attachment comprising a cylindrical shoe; a frangible plug with a longitudinal passageway connected to the shoe and projecting therefrom; valve means intermediate the passageway for preventing flow into the casing, said plug having a plurality of passages extending outwardly from the longitudinal passageway below the valve means and an annular header groove in its outer surface joining the outer ends of the passages; and a resilient sealing ring arranged to cover the groove and passage ends, said ring having its lower edge portion anchored in the plug.

7. A well casing attachment comprising a cylindrical shoe; a frangible plug with a longitudinal passageway connected to the shoe and having a pointed end projecting therefrom, said plug having four radial passages extending outwardly from the longitudinal passageway and an annular header groove in its outer surface joining the outer ends of the passages; and a resilient sealing ring closely encircling the lower end and arranged to cover the groove and passage ends, said ring having its lower edge portion reduced in thickness and anchored in the plug.

8. A formation packer comprising, in combination, a casing shoe; a pointed guide plug including a float valve joined to said shoe, said plug having a longitudinal passageway therein and a plurality of outwardly extending passages near its upper end connecting the passageway with the outer surface of the plug; and a long resilient ring of rubber complementally engaging the pointed outer surface of the plug so as to cover the passages with its upper end and to seal an adjacent formation hole with its lower end, the upper end of the ring being free to flex away from the plug to uncover the passages when fluid under pressure is forced therethrough.

9. A formation packer comprising, in combination, a casing shoe; a pointed guide plug includ-

ing a float valve joined to said shoe, said plug having a longitudinal passageway therein and a plurality of outwardly extending passages connecting the passageway with the outer surface of the plug; and a long resilient ring complementally engaging the pointed outer surface of the plug so as to cover the passages with its upper end and to seal an adjacent formation hole with its lower end, the upper end of the ring being free to flex away from the plug to uncover the passages when fluid under pressure is forced therethrough.

10. A formation packer comprising, in combination, a casing shoe; a tapered guide plug including a float valve joined to said shoe, said plug having a longitudinal passageway therein, a plurality of outwardly extending passages connecting the passageway with the outer surface of the plug and an annular header groove joining the outer ends of the passages; and a long resilient ring complementally engaging the tapered outer surface of the plug so as to cover the passages and groove with its upper end and to seal an adjacent formation hole with its lower end, the upper end of the ring being free to flex away from the plug to uncover the passages and groove when fluid under pressure is forced therethrough.

11. A formation packer comprising, in combination, a casing shoe; a tapered guide plug including a float valve joined to said shoe, said plug having a longitudinal passageway therein, a plurality of outwardly extending passages connecting the passageway with the outer surface of the plug, and a packer groove in its outer surface; and a long resilient ring complementally received in the packer groove of the plug on its tapered outer surface and disposed so as to cover the passages with its upper end and to seal an adjacent formation hole with its lower end, the upper end of the ring being free to flex away from the plug to uncover the passages when fluid under pressure is forced therethrough.

12. A formation packer comprising, in combination, a casing shoe; a pointed guide plug joined to said shoe, said plug having a longitudinal passageway therethrough and a plurality of outwardly extending passages connecting the passageway with the outer surface of the plug; and a long resilient ring complementally engaging the pointed outer surface of the plug so as to cover the passages with its upper end and to seal an adjacent formation hole with its lower end, the upper end of the ring being free to flex away from the plug to uncover the passages when fluid under pressure is forced therethrough.

DOMER SCARAMUCCI.
